US0D1105856S

(12) **United States Design Patent** (10) **Patent No.:** **US D1,105,856 S**
(45) **Date of Patent:** **** Dec. 16, 2025**

(54) **PORTABLE COOLER**

(71) Applicant: **Pacific Market International, LLC**,
Seattle, WA (US)

(72) Inventors: **Jeffrey Charles Munie**, Seattle, WA
(US); **Vignesh Chari**, Seattle, WA
(US); **Graeme Wagoner**, Seattle, WA
(US); **Melissa Metrolis-Poole**,
Richmond, TX (US)

(73) Assignee: **Pacific Market International, LLC**,
Seattle, WA (US)

(**) Term: **15 Years**

(21) Appl. No.: **29/917,811**

(22) Filed: **Nov. 22, 2023**

(51) LOC (15) Cl. **07-10**

(52) U.S. Cl.
USPC **D7/607**

(57) **CLAIM**

The ornamental design for a portable cooler as shown and described.

DESCRIPTION

FIG. 1 is a top perspective view of a portable cooler.
FIG. 2 is a bottom perspective view of the portable cooler of FIG. 1.

FIG. 3 is a front view of the portable cooler of FIG. 1.
FIG. 4 is a back view of the portable cooler of FIG. 1.

FIG. 5 is a right side view of the portable cooler of FIG. 1.

FIG. 6 is a left side view of the portable cooler of FIG. 1.

FIG. 7 is a top view of the portable cooler of FIG. 1.

FIG. 8 is a bottom view of the portable cooler of FIG. 1; and,
FIG. 9 is a top perspective view of the portable cooler of FIG. 1 in an open configuration.

The broken lines depict portions of the portable cooler that
form no part of the claimed design.

1 Claim, 9 Drawing Sheets
